UNITED STATES PATENT OFFICE.

OSCAR GLOVER, OF LOUISVILLE, KENTUCKY, ASSIGNOR TO GLOVER FUEL ECONOMIZER COMPANY INCORPORATED, OF LOUISVILLE, KENTUCKY.

FUEL-ECONOMIZER FOR INTERNAL-COMBUSTION ENGINES.

1,270,938.

Specification of Letters' Patent.

Patented July 2, 1918.

Application filed June 7, 1916, Serial No. 102,307. Renewed April 3, 1918. Serial No. 226,530.

To all whom it may concern:

Be it known that I, OSCAR GLOVER, a citizen of the United States, residing at Louisville, in the county of Jefferson and State 5 of Kentucky, have invented certain new and useful Improvements in Fuel-Economizers for Internal-Combustion Engines, of which the following is a specification.

The device which is the subject-matter of 10 the present application for patent is an attachment for motor vehicle engines of the internal-combustion type, and has for its object to reduce the amount of fuel consumed by the engine, and to obtain a maximum 15 speed and power with a minimum quantity of fuel.

The invention also has for its object to provide a device which prevents or minimizes carbon deposits on the intake and 20 exhaust valves of the engine.

A further object of the invention is to provide a novel and improved priming device.

The objects stated are attained by means 25 of a novel combination and arrangement of parts to be hereinafter described and claimed, reference being had to the accompanying drawing in which—

Figure 1 is a side elevation of the device 30 applied to the engine; Fig. 2 is a vertical section of the device, and Fig. 3 is an elevation thereof.

Referring specifically to the drawing, 5 denotes the engine of an automobile or other 35 motor vehicle, the engine being of the ordinary internal-combustion type and having an intake manifold 6 to which the carbureter 7 is connected. To the intake manifold, between the carbureter and the fuel 40 inlet of the engine cylinders, is connected an auxiliary air supply comprising a pipe 8 connected to a chamber 9 which is cylindrical in shape and closed at its ends, one of the closures being a removable screw plug 10 45 which is hollow for a purpose to be presently described. This chamber has a series of air-inlet apertures 12 located near the top thereof, and it is also provided with a side outlet at the bottom, to which a valve 13 is 50 connected. The delivery pipe 8 is connected to this valve, and intermediate its ends, said pipe is coiled around the exhaust pipe 14 of the engine, as indicated at 15, which is for a purpose to be presently described.

Alongside the chamber 9 is mounted an oil 55 reservoir 16, which may be an ordinary oil cup having a delivery pipe 17 which is connected to the valve 13. The flow of oil from the reservoir is controlled by a valve 18 having a stem 19 extending from the top 60 of the reservoir, and on the latter is mounted a support 20 for a valve operating lever 21 fulcrumed intermediate its ends to the support, as indicated at 22. One end of the lever is connected to the valve stem 19, and 65 its other end is connected to an operating rod 23, the lever having an aperture through which the rod loosely passes. Above the lever, the rod carries an abutment 24, which latter may be a nut, provided with a lock 70 nut 25, the rod being screw-threaded to receive the same. Thus, when the rod is drawn down, the lever is swung to open the valve 18. A valve-closing spring 26 is also provided. On the lower end of the rod is an 75 abutment 27, which latter may also be a nut screwed on the rod.

The valve 13 is a three-way valve having one side port and two end ports, the valve casing being so positioned that the end ports are in vertical alinement. The pipe 17 is connected to the top end port, and the pipe 8 is connected to the bottom end port, whereas the side port communicates with the outlet of the chamber 9. The valve proper is a 80 turning plug 13^a having ways corresponding to the valve casing ports. The valve plug has a crank arm 28 at one end on the outside of the casing to which is connected an operating rod 29 extending to a point 90 within easy reach of the driver. On the other end of the plug is a fork 30 into the path of which the abutment 27 extends. The pipe 17 carries a guide 31 for the rod 23. 95

The normal suction of the engine 5, while running, and the valve 13 being open, takes in air at the inlets 12, and in its passage to the intake manifold 6 the air is heated upon passing through the coil 15. The heated air entering the intake manifold mixes with 100 the fuel charges, resulting in the same being highly vaporized, thereby effecting a saving of fuel, it having been found that the speed of the engine is increased without increasing the fuel supply. 105

Upon turning the plug 13^a slightly, so that the fork 30 strikes the abutment 27, the rod 23 is drawn down, thereby opening the

oil valve 18, and upon restoring the plug to full open position, the fork is withdrawn from the abutment, to allow the oil valve to close. The oil dropping down the pipe 17 5 enters the valve 13 and passes straight through the way in the plug connecting the top and bottom ports to which the pipes 17 and 8 are connected, said pipes being here in vertical alinement. The air from the 10 chamber 9 enters the valve through the side port. Thus, it will be seen that the oil drops into the path of the current of air and is carried by the same into the intake manifold 6, and passes from the latter into the engine 15 cylinders. The mixture of air and oil is heated in its passage through the coil 15, and it enters the engine cylinders in the form of a fine spray, which lubricates the intake and exhaust valves, and prevents the accumulation 20 of carbon on the same and the stems thereof, the carbon being discharged with the exhaust. Excessive heating of the cylinders is also prevented.

The plug 10 is made hollow so that it 25 may serve as a reservoir to hold a small supply of gasolene for priming the engine. The bottom of the plug is closed by a removable screw cap 32 having an outlet into the chamber 9, said outlet being provided 30 with a valve 33 having an upstanding stem 34. In the top of the plug is an air vent 35 having an upstanding stem 36 projecting from the top of the plug and engageable by a flat spring 37 serving to normally hold said valve 38. From the bottom of the valve 35 depends a stem 39 having a socket 40 at its lower end into which the 40 upper end of the valve stem 34 loosely seats.

When it is desired to discharge gasolene from the plug 10 into the chamber 9, it is necessary only to press down on the stem 36, whereupon both valves open, the bottom 45 valve 33 admitting gasolene into the chamber 9, and the top valve 35 admitting air into the plug 10. Upon releasing the valve stem

36, the valves are at once closed by their springs.

In the chamber 9, below the plug 10, is a 50 sponge 41 or some other absorbent material.

In order to obtain a richer fuel mixture necessary when starting in cold weather, gasolene is let into the chamber 9 from the plug 10 by operating the valves thereof as hereinbefore described. The gasolene drops on the sponge 41, and the air upon passing through the latter vaporizes the gasolene and takes it to the intake manifold 6. The sponge also serves as a screen to keep dust 60 out of the cylinders.

The preferred embodiment of the invention has been shown and described, but it will be evident that various changes and modifications in the structural details may 65 be made without departure from the spirit and scope of the invention as claimed hereinafter.

I claim:

1. The combination with an internal-combustion engine; of a chamber having an air inlet and an outlet connected to the intake of the engine, a plug closing one end of the chamber, said plug being hollow to serve as a fuel reservoir, the inner end of the plug 75 having an outlet port into the chamber, and its outer end having a vent port, and valves for said ports.

2. The combination with an internal-combustion engine; of a chamber having an air 80 inlet and an outlet connected to the intake of the engine, a plug closing one end of the chamber, said plug being hollow to serve as a fuel reservoir, the inner end of the plug 85 having an outlet port into the chamber, and its outer end having a vent port, valves for said ports, and an operative connection between the valves.

In testimony whereof I affix my signature in the presence of two witnesses.

OSCAR GLOVER.
